Atty.

UNITED STATES PATENT OFFICE.

HENRY P. ROBERTS, OF BOSTON, MASSACHUSETTS.

PENCIL-HOLDER.

1,245,972.

Specification of Letters Patent.

Patented Nov. 6, 1917.

Application filed November 15, 1916. Serial No. 131,419.

To all whom it may concern:

Be it known that I, HENRY P. ROBERTS, a citizen of the United States, residing at Boston, county of Suffolk, State of Massachusetts, have invented a certain new and useful Improvement in Pencil-Holders, of which the following is a specification, reference being had therein to the accompanying drawings.

10 My invention has for its object a novel holder for pencils or the like which is provided with a strip of paper, fabric or other suitable material wound up within the holder on a spring roller. The device is so arranged that the strip may be readily drawn out at one side of the holder when desired to be used, and when released will automatically wind up on the roller within the holder so that the pencil may be employed for writing or the like. The fabric strip is adapted to have a calendar or like matter printed thereon and is printed on one side only, the other side being left blank for memoranda, such as a telephone list. In order to facilitate the use of the strip I provide means for engaging the strip when drawn out to retain it in its drawn out position.

25 My invention will be fully understood when taken in connection with the accompanying drawings and the novel features will be pointed out and clearly defined in the claim at the close of this specification.

In the drawings, Figure 1 is an elevation of a device embodying my invention.

30 Fig. 2 is a longitudinal section showing the printed strip partly drawn out.

Fig. 3 is a transverse section on line 3—3 of Fig. 2.

Having reference to the drawings there is shown a holder of tubular shape which may consist of any well known material such as wood, hard rubber, fiber board or the like. The holder comprises a main portion 11 and a pencil holding portion 12 of less diameter than the portion 11 and adapted to receive a pencil 13. At 14 is shown a slot which is parallel with the axis of the holder through which a fabric strip 15 or the like is adapted to pass. The free end of the strip 15 is provided with a bead member 9 which is somewhat larger than the slot 14 and affords a convenient means for pulling out the strip from the holder or case 11, and said member 9 also serves as a stop to limit the inward movement of the strip 15 when the

latter is drawn into said holder or case by its torsional winding spring.

Within the holder is journaled a roller 16 one end of which rotates in a bearing 17 formed at the junction of portions 11 and 12 of the holder and the other end of which is adapted to rotate in a cap 18. The cap 18 is preferably formed as shown being provided with a shank 19 adapted to be received in the end of the holder and to be secured thereto in any suitable manner such as by adhesive or the like. A hole 20 through the cap 18 forms a bearing for the roller 16. The roller 16 is enlarged as shown at 21 and upon the enlarged portion the strip 15 is adapted to be wound being secured to the same in any suitable manner such as by adhesive.

The part 22 of the roller is surrounded by a spiral spring 23 which operates to rotate the roller and wind up the strip of paper 15. In order to secure the spring 23 to the roller so that the device may be readily assembled and inexpensively constructed, I provide the spring 23 with a bent end 24 which is adapted to fit within a hole 25 in the shoulder 26 formed by the portion 21. In the same manner I provide the other end of the spring 23 with a bent end 27 which is adapted to be received within a corresponding hole 28 in the cap 18. In the construction shown the roller 16, with the strip 15, wound thereon, is inserted in the case or holder 11, when the cap 18 is removed. The end of the said strip is then drawn out through the slot 14 and the bead stop member 9 is then attached to the end of the said strip by an adhesive, said end being received in a groove in said stop member. The cap 18 is then inserted in place and one end of the spring 23 entered in the hole 28 in the said cap. A proper torsional stress may now be given to the spring 23 by turning said cap, and the latter will afterward be retained in place either by friction or by an adhesive which has been applied to the shank 19 thereof. In the operation of thus winding up the spring 23 the roller on which the strip 15 is wound will be prevented from turning by the bead stop 9.

Means for retaining the strip 15 of paper or the like in drawn-out position, so that it may be readily used as a memorandum sheet, consists of a clip 29, preferably of spring metal, which partially surrounds and frictionally engages the holder or case 11, said clip having a snug fit on said case. The clip

29 is provided with an out-turned end 30 which may be pressed against by the finger of the user when it is desired to engage its opposite blunt end with the strip 15 of ribbon, paper or the like, when the clip is to be partially turned about the holder or case 11, and thus cause said clip to serve as a stop to prevent said strip 15, when pulled out, from being drawn into the holder or case 11 until 10 said clip is released from said strip.

The device embodying my invention is particularly adapted for use as an advertising novelty, the strip affording abundant space for advertising matter in addition to 15 any other printed matter desired.

What I claim is:

In a device of the character described, the combination with a tubular holder provided

with a slot in one side, of a spring-actuated roller mounted in said holder, a strip to be 20 wound on said roller by the force of its spring, said strip extending outward through said slot, a spring metal clip partly surrounding and frictionally engaging said holder and having a blunt end adapted to 25 be forced, by a partial turning movement about said holder, into frictional engagement with said strip, so that said clip will serve as a stop to hold said strip in any desired drawn-out position in opposition to 30 the stress of said spring, the opposite end of said clip being slightly out-turned for convenient engagement when said strip is to be partially turned on said holder.

In testimony whereof I affix my signature. 35

HENRY P. ROBERTS.
